UNITED STATES PATENT OFFICE.

HENRY UNTERMEYER, OF NEW YORK, N. Y.

DESIGN FOR A WATCH-CASE.

SPECIFICATION forming part of Design No. 12,574, dated November 15, 1881.

Application filed September 14, 1881. Term of patent 3½ years.

To all whom it may concern:

Be it known that I, HENRY UNTERMEYER, of New York, in the county and State of New York, have invented a Design for Watch-Cases, 5 of which the following is a specification.

The distinctive characteristics of the design are shown in the accompanying photographic illustration.

The design is in the nature, first, of an elaborate frame, which is applied to occupy the outer parts of the case or cases of the watch. The inner part of the frame consists of a series 10 of dots forming an oval, and presenting the appearance of beaded work, supplemented above and below by scroll-work.

The second part of the design consists of a stag occupying the foreground of a landscape scene, and applied upon the central parts of the watch-case.

20 Displayed concentrically with the series of dots resembling beaded work above-mentioned is a conventional wreath, part of which is formed of the scroll-work hereinbefore described as being connected with the inner part 25 of the design, the whole being harmonized to produce the effect shown in the said photographic illustration. The stag and landscape are inclosed by the frame and beaded work, the stag being the most prominent feature of the scene.

30 The subject-matter of the first claim of this application is shown in another application filed by me on the 14th day of September, 1881, but is not claimed therein.

What I claim as my invention, and desire 35 to secure by Letters Patent, is—

1. The design for a watch-case, consisting of the oval formed of dots and presenting the appearance of beaded work, substantially as described.

40 2. A design for a watch-case, consisting of a representation of a stag displayed to occupy the central field of the case, substantially as described.

Witness my hand this 12th day of September, A. D. 1881.

HENRY UNTERMEYER.
